UNITED STATES PATENT OFFICE.

OTTO A. HOKANSON, OF WOODSTOCK, ILLINOIS, ASSIGNOR TO WOODSTOCK TYPE-WRITER COMPANY, OF WOODSTOCK, ILLINOIS, A CORPORATION OF ILLINOIS.

RIBBON VIBRATOR FOR TYPEWRITERS.

Application filed May 29, 1920. Serial No. 385,185.

To all whom it may concern:

Be it known that I, OTTO A. HOKANSON, a citizen of the United States, residing at Woodstock, in the county of McHenry and 5 State of Illinois, have invented certain new and useful Improvements in Ribbon Vibrators for Typewriters, of which the following is a specification.

This invention has for its object the 10 provision of mechanism of the class named which shall be of improved construction and operation.

The invention is exemplified in the combination and arrangement of parts shown in 15 the accompanying drawings and described in the following specification, and it is more particularly pointed out in the appended claims.

In the drawings—

20 Fig. 1 is a front elevational view of a portion of a typewriter showing the present invention applied thereto;

Fig. 2 is a top plan view of the mechanism shown in Fig. 1; and

25 Fig. 3 is an elevation looking from the right in Fig. 2.

In the drawings the invention is illustrated as applied to a typewriter provided with a folding frame for supporting the 30 platen carriage, and while the invention is especially adapted for use in connection with a typewriter of this kind, it is understood that it is not confined to any particular form of typewriter except as set forth in the 35 claims.

The typewriter shown in the drawings is provided with a main frame 10 having arms 11 pivoted thereon for supporting a platen carriage bed plate 12. A platen carriage 40 13 is mounted on the bed plate 12 and is movable thereon along ways 14 provided with ball bearings 15. A platen roll 16 is supported on the carriage 13 in any usual and well-known manner.

45 Secured to the bed plate 12 by rivets or screws 17 is a bracket plate 18 on which is mounted the various parts of the ribbon-shifting mechanism. The bracket plate 18 has a portion of the front edge thereof bent 50 upwardly to form an upright flange 19 to which a type bar guide 20 is secured by means of screws 21. The guide plate 20 is provided with forwardly extending lips 22 for guiding the type bars into printing position. The lips 22 are supported on the

plate 20 by upright bars 23 and a ribbon carrier 24 is arranged to slide vertically against the rear face of the bars 23 and is held in position by tongues 25 bent around the lateral edges of the uprights 23. The upper 60 end of the ribbon carrier 24 is bifurcated and each branch is provided with fingers 26 for holding a ribbon. The lower end of the carrier is pivoted at 27 to an arm 28 of a bell crank lever 29. The bell crank lever 65 29 is mounted on a pivot 30 carried by a flange 31 bent upwardly from the bracket plate 18. An arm 32 of the bell crank lever 29 extends downwardly and has its lower end widened and provided with notches 33, 70 34 and 35.

As shown best in Fig. 2, a lever 36 is pivotally supported at 37 on the lower face of the bracket plate 18 and is provided with arms 38 and 39 extending laterally from its 75 pivotal support. The lever 36 is provided with a forwardly extending portion 40 which carries downwardly projecting lugs 41. A yoke 42 is provided with arms 43 pivotally connected to the lugs 41 by a pin 80 44. A spring 45 surrounds the pin 44 and tends to rotate the yoke 42 forwardly. A finger-piece 46 projects forwardly from the yoke 42 and carries a lug 47 arranged to selectively engage the notches 33, 34 and 35. 85 It will be apparent that the spring 45 will hold the lug 47 in contact with any particular notch engaged thereby and that the lug can be shifted from one to the other of the three notches by pressing downwardly on the finger-piece 46 and shifting the finger-piece and the lever 36 connected therewith to bring the lug 47 into engagement with any one of the three notches. The amount of rotation of the yoke 42 about the pin 44 90 is limited by a stop 42' on the rear of the yoke and the two outermost prongs of the notched end of the lever arm 32 are longer than the intermediate prongs to prevent the lug 47 from passing out of engagement with 95 the notched end of the lever arm.

The arm 38 of the lever 36 is provided with a downwardly extending projection 48 which is positioned in the path of movement of a universal member 49. The member 49 is operated by the key levers in any well-known manner so that it is moved forwardly whenever a key is struck. The forward movement of the universal member 49 will cause it to engage the projection 48 100 105 110

and shift the lever 36 about its pivot 37. The movement of the lever will carry the yoke 42 and the lug 47 thereon to the left, as viewed in Fig. 1, which movement will 5 shift the bell crank lever 29 in a clockwise direction, as viewed in that figure. The shifting of the bell crank lever 29 will raise the arm 28 into one of the positions indicated by broken lines in Fig. 1 and designated by the letters B and C. If the lug 47 is in engagement with the notch 33 the arm 28 will be raised to position B. If, however, the lug 47 is in engagement with notch 35 the projection 48 will be in position to 15 contact more quickly with the universal member 49, and hence the bell crank lever 29 will be given a greater movement and will be raised to position C. If the lug 47 is shifted to the left, as viewed in Fig. 1, into 20 engagement with notch 33 the projection 48 will be swung forwardly beyond the path of movement of the universal member 49 so that the operation of the universal member will not change the position of the bell crank 25 lever 29 and the arm 28 will remain in its lowermost position designated by the character A. The ribbon carrier 24 will usually be provided with two-color zones, the upper one of which may be black and the lower one red. When the arm 28 is shifted into 30 position B the black zone will be raised into printing position, and if the arm is shifted into position C the red zone will be brought into the printing line. When the arm is in 35 position A the ribbon is below the printing line so that if the lug 47 is moved to engage notch 33 the ribbon will remain stationary below the printing line during the operation of the key levers. This is the position of 40 the lug 47 and finger-piece 46 for cutting stencils.

As shown in Fig. 2, a spring 50 is connected to the arm 39 of the lever 36 and normally draws the arm 39 forwardly to 45 hold the ribbon carrier 24 in its lowermost position with the arm 32 in contact with a limit stop 32' on the flange 31. A stop 51 is provided for limiting the movement of the lever 36 in the opposite direction and the 50 arm 39 is provided with a plurality of openings 52 for receiving the end of the spring 50 to vary the tension of the spring upon the lever 36.

It will be seen that the invention provides 55 a ribbon vibrator in which all of the parts are connected with the platen carriage so that they may be folded with the carriage into and out of its operating position without breaking the operative connection between the parts. The movement of the carriage into operating position automatically 60 brings the vibrator into position to be operated by the universal member which is actuated by the key lever mechanism carried by 65 the base frame of the machine. The ribbon

vibrator always returns to the same initial position to leave the printing line uncovered and the mechanism may be adjusted to vary the throw so that different portions of the ribbon will be employed for printing, or, it 70 may be adjusted so that the ribbon remains idle when the key levers are operated. The mechanism is simple and the parts are all compactly arranged so that they may be supported on the platen carriage frame 75 without interfering with the other parts of the typewriter.

I claim:

1. In a typewriter, a ribbon carrier, a lever for actuating said carrier to shift the ribbon thereon, an operating member for said lever, and means for connecting said operating member with said lever at different positions on said lever displaced angularly relative to one another with respect to the fulcrum of said lever to cause said operating member to impart different amounts of movement to said lever.

2. In a typewriter, a ribbon carrier, a lever for actuating said carrier to shift the ribbon thereon, an operating member for said lever, and means on said operating member for engaging said actuating lever at a plurality of positions thereon disposed at different angles with respect to the fulcrum of said lever, so that said operating member when moved to a fixed limit of travel will shift said lever different amounts, said engaging means being movable into and out of operative connection with said lever to permit the shifting of said operating member relative to said lever.

3. In a typewriter, a ribbon carrier, means for actuating said carrier to shift the ribbon thereon, an operating member for said actuating means, a universal member for moving said operating member, and an adjustable connection between said operating member and said actuating means to permit shifting of said operating member toward and away from said universal member so that different amounts of movement will be transmitted to said ribbon carrier for a given movement of said universal member.

4. In a typewriter, a platen carriage movable into and out of operating position, a ribbon carrier movably mounted on said carriage; a lever for actuating said carrier to shift the ribbon thereon; a second lever for operating said actuating lever; a spring for normally returning said actuating lever to a fixed initial position; an adjustable connection between said levers to vary the position of said operating lever when said actuating lever is in initial position; and means for moving said operating lever to a fixed limiting position to impart different amounts of movement to said actuating lever and said ribbon carrier for the dif-

ferent adjustments of said levers relative to one another.

5. In a typewriter having a platen carriage arranged to move into and out of operating position; a ribbon carrier movably mounted on said carriage; an actuating lever for said carrier; a spring for normally holding said actuating lever and carrier in a fixed initial position; a lever 10 for operating said actuating lever; an adjustable connection between said levers to vary the position of said operating lever when said actuating lever is in initial position; and a universal member arranged to 15 cooperate with said operating lever when said platen carriage is in operating position and to move said operating lever to a fixed limiting position to impart different amounts of movement to said actuating lever and 20 said ribbon carrier for the different adjustments of said levers relative to one another.
6. In a typewriter, a platen carriage arranged to move into and out of operating 25 position; a ribbon carrier movably mounted on said carriage; a member for actuating said carrier to shift said ribbon; a device for operating said actuating member; means arranged to cooperate with said operating 30 device when said carriage is in operating

position and to move said operating device to a limiting position; and an adjustable connection between said actuating member and said operating device for setting said operating device in different initial positions at different distances from its said cooperating means, said connection in one position being arranged to permit said actuating member and said ribbon carrier to remain stationary when the means for moving said operating device is operated and to impart different amounts of movement to said actuating member and ribbon carrier for other positions of adjustment. 35

7. A ribbon vibrator for typewriters 40 comprising a ribbon holder, a pivoted member for operating said holder, an actuating device for said pivoted member, means for moving said actuating device from different starting positions to a fixed limit of movement, and means for connecting said actuating device with said pivoted member at 45 points on said pivoted member having different angular positions relative to the pivotal center thereof but spaced substantially equal distances from said center. 50

In testimony whereof I have signed my name to this specification on this 24th day of May A. D. 1920.

OTTO A. HOKANSON.
